UNITED STATES PATENT OFFICE.

THEODORE DICKMAN AND JOHN W. ELLIOTT, OF WAPAKONETA, OHIO.

DESIGN FOR A CHURN-FRAME.

SPECIFICATION forming part of Design No. 15,046, dated June 10, 1884.

Application filed March 15, 1884. Term of patent 14 years.

To all whom it may concern:

Be it known that we, THEODORE DICKMAN and JOHN W. ELLIOTT, of Wapakoneta, in the county of Auglaize and State of Ohio, have invented and produced a new and useful Design in Churn-Frames, of which the following is a specification, reference being had to the accompanying cut, which represents a perspective view of our design.

10 A represents the body of the churn, consisting of a U-shaped bottom, A', having a mottled appearance, sides A² A², and top pieces,

A³, one of which is shown. B represents the cover, having pieces B' B'. C represents the legs, curved and formed as shown.

What we claim as new is—

The churn-frame, substantially as shown and described.

THEODORE DICKMAN.
JOHN W. ELLIOTT.
